UNITED STATES PATENT OFFICE.

GEORGE F. CASE, OF CLAREMONT, NEW HAMPSHIRE.

CORE-LIFTER FOR ANNULAR ROCK-DRILLS.

SPECIFICATION forming part of Letters Patent No. 247,303, dated September 20, 1881.

Application filed August 8, 1881. (No model.)

To all whom it may concern:

Be it known that I, GEORGE F. CASE, of Claremont, in the county of Sullivan and State of New Hampshire, have invented a new and Improved Core-Lifter for Annular Rock-Drills; and I do hereby declare that the following is a full and exact description of the same, reference being had to the accompanying drawings, and to the letters of reference marked thereon.

10 This invention relates to an improvement in core-lifters for annular rock-drills; and it consists in making a tapering recess in the tubing next above the drill-head in such a way that the bottom of the coupling and the top of the 15 drill-head make upper and lower shoulders to such recess, and in combining with such recess a split spring-tube, into which wedges are fitted loosely, all as more fully hereinafter described.

To enable those skilled in the art to know 20 how to make and use my invention, I will proceed to fully describe the same, reference being had to the accompanying drawings, in which—

Figure 1 is a longitudinal section of the core-lifter and annular drill to which it is applied; 25 Fig. 2, a transverse section of the spring-tube on the line xx of Fig. 1, with the wedges inserted; Fig. 3, a detail view of the spring-tube with the openings cut therein, and Fig. 4 a detail view of one of the wedges.

30 Like letters denote corresponding parts in each figure.

A represents the drill-head screwed into the section of tubing B, which, in turn, is connected to the drill-rod by the coupling C. The inner 35 side of the tubing B is made tapering, decreasing in size downwardly, thus forming a recess, c, in said tubing, as shown in Fig. 1. The lower end of the coupling C terminates at the larger and upper end of the recess, there forming a 40 shoulder, a, and the upper end of the drill-head in like manner terminates at the lower and smaller end of said recess, thus forming a shoulder, b. Within this recess the spring-tube D and its wedges d have movement up and down, which movement is terminated in either direction by the shoulders a b. The spring-tube D, split from end to end, so as to allow of sufficient contraction and expansion, has two or more

openings, d', as may be desired, cut in its sides, of sufficient length and width to receive and hold loosely the wedges d, one of these openings being shown in Fig. 3. The wedges d are of the construction shown in Fig. 4, the outward projection thereon being the portion that enters the opening d' of the spring-tube and clamps the core, as may be seen by reference to Fig. 1. These wedges should be made of hardened steel or iron, while the tube can be of spring temper. There should be enough space left between the outer sides of the wedges and the 50 tapering sides of the recess to allow the drill to revolve without revolving the tube, the wedges of which, by the spring of the tube, are pressed against the core. There should also be space enough in the openings d of the spring- 55 tube to permit the wedges to have plenty of play in said openings.

In its operation the spring-tube D hugs the core, but allows it to pass up through it, the tube moving with it toward the upper and larger 60 part of the recess, and prevented from revolution by its spring contact with the core. When the ring comes in contact with the shoulder a of coupling C it stops and there remains until the required depth is reached and it is desired 65 to break off the core. When the drill-rod is raised the movement causes the wedges to be drawn into the smaller end of the recess, clamping it firmly against the core and breaking off the core, which is raised with the drill-rod and 70 easily removed therefrom in the ordinary manner.

I am aware that core-lifters have been invented wherein a tapering recess with shoulders was made in a section of the tubing, but such recesses are expensive to make if turned up smoothly, as they should be; and also that in such recesses cut-steel rings have been used as core-lifters, such rings having thick portions armed with rough diamonds or carbon, but such rings are expensive and soon get out of order. In the invention herein described both 75 of these inconveniences are avoided.

The recess in the tubing can be bored or planed out smoothly without difficulty, and the 80 wear of the core-lifter comes upon the wedges,

which are very hard, and from their form may wear a long time and remain effective, and finally may be removed at a small expense.

Having described my invention, what I claim
5 is—

1. In combination with the drill-head A and the coupling C, forming upper and lower shoulders, the intermediate recessed tubing, B, substantially as described.
- 10 2. In combination with the recessed tubing

B, the split spring-tube D, having wedges d, constructed and arranged substantially as described.

This specification signed and witnessed this 16th day of May, 1881.

G. F. CASE.
